(57) **CLAIM**

The ornamental design for a jack plate bracket, as shown and described.

DESCRIPTION

FIG. 1 is a front elevational view of the jack plate showing my new design;

FIG. 2 is a rear elevational view thereof;

FIG. 3 is a side left elevational view thereof, the right side view is a mirror image of the left side view;

FIG. 4 is a top plan view thereof; and

FIG. 5 is a bottom plan view thereof; and,

FIG. 6 is a cross section of FIG. 3, showing the indentation, or recess, of the surface, as depicted in FIG. 3 with the broken lines.

The broken lines shown in the drawings represent unclaimed portions of the jack plate bracket and form no part thereof.
